UNITED STATES PATENT OFFICE.

FRANCIS I. MAULE, OF PHILADELPHIA, PENNSYLVANIA.

SCREW-CUTTING DIE.

SPECIFICATION forming part of Letters Patent No. 380,908, dated April 10, 1888.

Application filed December 7, 1887. Serial No. 257,204. (No model.)

To all whom it may concern:

Be it known that I, FRANCIS I. MAULE, a citizen of the United States, and a resident of Philadelphia, Pennsylvania, have invented 5 certain Improvements in Screw-Cutting Dies, of which the following is a specification.

The object of my invention is to so construct a screw-cutting die that the cost of manufacture will be reduced to a minimum, the cutting-bits rigidly supported in the stock, and provision afforded for the ready removal and replacing of any one of said bits. This object I attain in the manner which I will now proceed to describe, reference being had to the accompanying drawings, in which—

Figure 1 is a perspective view of a screw-cutting die constructed in accordance with my invention. Fig. 2 is a sectional plan view of the same; and Fig. 3 is a transverse section on 20 the line 1 2, Fig. 2.

The stock of the die consists of a block, A, preferably of malleable iron or cast-steel, and of the cruciform shape shown in the drawings, for the purpose of reducing its weight, although the block may, if desired, be rectangular, as shown by dotted lines in Fig. 2. In this block are formed radial recesses for the reception of the cutting-bits *a*, which fit snugly in these recesses, the back of each bit having 30 a rigid bearing against the base of the slot and the sides of the bit bearing against the sides of the slot. The bits are retained in the slots by means of transverse pins *b*, driven through openings in the bits and in the arms 35 of the block, or across the corners of the same if the block is of rectangular form. These pins, however, are not intended to resist the strain upon the cutting-bits in the operation of the tool, but are simply for holding the bits 40 in place, reliance being placed upon the rigid bearing of the bits against the sides and bases of the slots in the block to withstand any strain to which said bits may be subjected in the operation of the tool. The slots for the recep-

tion of the bits extend through from face to 45 face of the block A, and are of uniform size and shape throughout, so that they may be readily made true by means of a drifting-tool passed through from one face of the block to the other.

Although the cutting-bits are firmly retained in the block, any one of the bits can be readily removed by driving out the transverse retaining-pin, and a new bit can then be inserted and as readily secured in place by the reinsertion of the pin.

It will be seen that my improved screw-cutting die comprises but few parts, and that no expensive fitting is demanded in the construction of the same, so that the tool can be manufactured very cheaply, this cheapness of manufacture resulting without any impairment of the efficiency of the tool.

I claim as my invention—

1. The combination of the block having slots 65 extending completely through the same from face to face, and having opposite sides parallel from face to face of the block, with cutting-bits fitting snugly in said slots, and transverse retaining-pins passing through openings in the 70 block and bits, all substantially as specified.

2. The combination of the block having a central opening, and slots extending outward therefrom, with cutting-bits fitting snugly in said slots and bearing at their outer ends 75 against the bases of the slots, and transverse pins passing through openings in the block and bits and serving to cause said bits to bear firmly against the outer bearings in the block, all substantially as specified.

In testimony whereof I have signed my name to this specification in the presence of two subscribing witnesses.

FRANCIS I. MAULE.
